UNITED STATES PATENT OFFICE.

CHARLES A. BAILEY, OF MIDDLETOWN, CONNECTICUT.

MECHANICAL TOY.

SPECIFICATION forming part of Letters Patent No. 281,427, dated July 17, 1883.

Application filed March 3, 1883. (No model.)

To all whom it may concern:

Be it known that I, CHARLES A. BAILEY, a citizen of the United States, residing at Middletown, in the county of Middlesex and State 5 of Connecticut, have invented certain new and useful Improvements in Mechanical Toys; and I do declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 Figure 1 of the drawings is a side view of my toy, and Fig. 2 is a top or plan view of the same.

This invention has relation to mechanical 20 toys; and it consists in the construction and novel arrangement upon a wheel-mounted frame of a vibratory support carrying a ball or other object, end figures, between which the ball or other object passes back and forth during the vibrations, and a crank device operating 25 the vibratory support when the toy is in motion; and the invention further consists in providing, in combination with the vibratory support and its ball or other object, pivoted or yielding end figures adapted to be put in 30 motion by the impact of the vibratory object, all as hereinafter set forth.

In the accompanying drawings, the letter A designates a frame supported on wheels B. The shaft C, connecting one pair of wheels, is 35 formed with a crank, D.

E represents a vibratory support having an upward extension or arm, e, and a downward extension or arm, e', the support being pivoted to the main frame, as indicated at g. The arm 40 e', which extends downward from the pivotal portion of the support, is connected by means of a small wire or pitman, h, to the crank d,

so that when the toy is moved along the floor, causing its wheels to turn, the vibratory support will be moved back and forth. To the 45 upper end of the arm e of the vibratory support is attached a ball, k, or other small object.

At each end the frame A is provided with a support or bearing, l, to which is pivoted the figure of a boy, monkey, or other animated 50 being, as indicated at N, the figure having arms or projections m in position to be engaged by the vibrating ball or object k. To the lower end of this figure is usually connected a bell or jingle, as indicated at m'. 55

When the toy is dragged over the floor, the ball will appear to be thrown from one figure to the other, as its support vibrates back and forth. When the figures are pivoted, as shown in the drawings, the impacts of the ball will 60 put them alternately in motion, and will cause the bell to sound.

Having described this invention, what I claim, and desire to secure by Letters Patent, 65 is—

1. A mechanical toy consisting of a wheel-mounted frame supporting end figures, and having between the end figures a vibratory support carrying a ball or other object, and operated by means of a crank on the wheel-shaft and connection, substantially as specified. 70

2. In a mechanical toy, the combination, with a vibratory support operated by a crank on the wheel-shaft, and carrying a ball or other small object, of pivoted or yielding end figures 7 connected to bearings on the frame, and adapted to be put in motion by the impact of the vibratory object, substantially as specified.

In testimony whereof I affix my signature in presence of two witnesses.

CHAS. A. BAILEY.
